UNITED STATES PATENT OFFICE.

JOHN G. STEWART, OF CARLINVILLE, ILLINOIS.

DESIGN FOR PHOTOGRAPHS.

Specification forming part of Design No. 5,857, dated May 14, 1872.

Specification describing a Design for the Improvement of Photographs, invented by JOHN G. STEWART, of Carlinville, in the county of Macoupin, State of Illinois.

The nature of my design is fully represented by the accompanying photograph.

A presents the photograph in the center. Nos. 1 2 3 are circles or medallion shades, which give the photograph the appearance of a porcelain picture, and gives a depth and beauty that cannot be produced by any other process. The circles are made by the photographic process, and any shade or color can be made to

suit the pictures, which are produced by the use of mats, masks, or diaphragms, as they may be called by either name.

I do not claim the photograph A as my invention; but—

What I do claim is—

The "colored circles" around it, as an improvement on all other styles of photograph prints, of any size.

JOHN G. STEWART.

Witnesses:

I. G. PEEBLES,
Rev. HUGH LAMONT.
